GOLF CLUB

Filed July 26, 1928

Inventor

William H. Anderson
By S. S. Thomas

Attorney

UNITED STATES PATENT OFFICE.

WILLIAM H. ANDERSON, OF DETROIT, MICHIGAN.

GOLF CLUB.

Application filed July 26, 1928. Serial No. 295,495.

My invention relates to an improvement in golf clubs shown in the accompanying drawings and more particularly described in the following specification and claims.

- 5 It is well-known among golfers that the principal difference between the various iron and brass clubs used in playing golf consists in the angle at which the striking surface of the blade is presented to the ball and struck 10 thereby. These different angled clubs are necessitated by the position of the ball on the ground,—the condition of the ground when the stroke is made,—and the distance of the ball from the hole.
- 15 The primary object, therefore, of my invention is to provide a single, strong, simple and inexpensive form of club which is so constructed that the blade or head may be set at different angles relative to the shaft, the blade 20 being rigidly secured in its adjusted position so as to prevent all rattle or lost motion between the parts.

With the foregoing and other objects in view which will appear as the description proceeds, the invention further resides in the details of construction hereinafter described and claimed, it being understood that changes may be made in the precise embodiment of the invention without departing from the spirit 30 of the same.

In the drawings accompanying this specification:

- Figure 1 is an elevation of a golf club with parts in section.
- 35 Figure 2 is a cross-sectional view through the handle at the upper end of the shaft, showing means for adjusting the flexible rod connected with the head, whereby the head is rigidly secured upon the outwardly extending tubular stem of the shaft.

Figure 3 is a cross-sectional view through the upper end of the shaft.

- Figure 4 is a fragmentary elevation of the lower end of the shaft with its outwardly extending stem and integral cone-shaped portion, removed from the cone-shaped socket of the head.

Referring now to the letters of reference placed upon the drawings:

- 50 A is a tubular shaft terminating at its lower end in an outwardly extending tubular stem A¹, projecting at an angle to the body of the shaft. A² is a cone-shaped enlargement integral with the stem, preferably

formed with a "ground" or milled outer surface.

B is a blade or head bored to receive the stem, formed with a cone-shaped "ground" or milled socket B¹ to receive and co-ordinate with the cone A² on the stem of the shaft, 60 whereby the parts may be secured in fixed adjustable relation to each other.

C denotes a flexible rod provided at one end with a head C¹ of preferably cone-shaped form, seated in a correspondingly shaped recess in the outer end of the head.

The rod C extends through the hollow stem and integral shaft and is threaded at its upper end to receive a milled nut D having a relatively long tubular sleeve projecting into 70 an enlarged bore E in the end of the shaft.

F is a guide block for the rod C, preferably hexagonal in cross-section, supported in a bushing G lodged in the enlarged bore of the 75 shaft.

H denotes a pin extending through the shaft into the bushing to secure the latter against displacement. I indicates a leather wrapping forming the usual handle covering the end of the shaft.

Having now indicated the several parts by reference letters, the construction and means for adjusting the club will be readily understood.

To adjust the head B of the club to any desired angle the nut D is first turned so as to release the flexible rod C sufficiently to permit the head being turned freely upon the stem,—the cone A² is thus freed from its impinging locking contact with the wall of the 90 socket. The head may then be turned upon the projecting stem to effect the desired adjustment of the blade in relation to the shaft.

When this has been satisfactorily accomplished, the nut D is adjusted upon the flexible rod drawing the head toward the cone A², on the stem of the shaft, that it may again impinge upon the wall of the socket in which it is seated,—thus securely locking the blade at the angle desired.

While I have shown an adjustable nut engaging the end of the rod to force the blade into interlocking engagement with the cone-shaped enlargement on the stem of the shaft,—it is apparent that other means may be employed to secure this adjustment.

And so also while I prefer to employ a flexible rod to maintain the head in locked

relation with the shaft, a cable or chain may be used in lieu of the flexible rod if desired.

Having thus described my invention what I claim is:

5. 1. An adjustable golf club comprising a tubular shaft having a stem extending at an angle thereto with a cone-shaped enlargement on the stem adjacent the shaft; a rotatably adjustable and longitudinally movable blade bored to receive the stem and provided with a cone-shaped socket to receive and seat the cone-shaped enlargement on the stem; a flexible rod extending through the stem and shaft having an enlarged head at one end seated against the outer end of the blade, its opposite end being 10 screw threaded to receive a nut; an adjustable nut having a relatively long screw threaded depending apron screwed upon the flexible rod and extending into an enlarged bore in the upper end of the tubular shaft; a guide sleeved upon the rod; a bushing supporting said guide in the enlarged bore of the tubular shaft; and means for securing the bushing against displacement. 40
15. 2. An adjustable golf club comprising a tubular shaft and stem projecting at an angle to the shaft with a cone-shaped enlargement on the stem adjacent to the shaft; a rotatably adjustable and longitudinally movable blade bored to receive the stem and provided with a cone-shaped socket to receive and seat the cone-shaped enlargement on the stem; a flexible rod extending through the stem and shaft having an enlarged head at one end seated against the outer end of the blade, its opposite end being 45 screw threaded to receive a nut; and an adjustable nut located at the upper end of the shaft and having a relatively long screw threaded depending apron screwed upon the flexible rod and extending into an enlarged bore in the upper end of the tubular shaft. 50
20. 3. An adjustable golf club comprising a tubular shaft having a stem extending at an angle thereto with a cone-shaped enlargement on the stem adjacent the shaft; a rotatably adjustable and longitudinally movable blade bored to receive the stem and provided with a cone-shaped socket to receive and seat the cone-shaped enlargement on the stem; a flexible rod extending through the stem and shaft having an enlarged head at one end seated against the outer end of the blade, its opposite end being 55 screw threaded to receive a nut; an adjustable nut having a relatively long screw threaded depending apron screwed upon the flexible rod and extending into an enlarged bore in the upper end of the tubular shaft; a guide sleeved upon the rod; a bushing supporting said guide in the enlarged bore of the tubular shaft; and means for securing the bushing against displacement. 60
25. 4. An adjustable golf club comprising a tubular shaft having a stem extending at an angle to the shaft with a cone-shaped enlargement on the stem adjacent the shaft; a rotatably adjustable and longitudinally movable blade bored to receive the stem and provided with a cone-shaped socket to receive and seat the cone-shaped enlargement on the stem; a flexible rod extending through the stem and shaft having an enlarged head at one end seated against the outer end of the blade; and means engaged with the 65 other end of the rod and located at the handle end of the shaft to force the blade into interlocking relation with the cone-shaped enlargement on the stem of the shaft. 70
30. In testimony whereof, I sign this specification. 75

WILLIAM H. ANDERSON.
